WINDOW SASH GUIDE

Arthur M. Starck, and William R. Starck, Greenwich, Conn., assignors to A.M.S. Corporation, South Norwalk, Conn.

Filed Feb. 24, 1970, Ser. No. 21,570

Term of patent 14 years

Int. Cl. D25—03

U.S. Cl. D13—6

FIG. 2

FIG. 1

FIG. 3

FIG. 4

FIG. 5

FIG. 6

FIG. 1 is a rear perspective view of a portion of a window sash guide for tilttable double-hung windows, embodying our new design.

FIG. 2 is a front elevation view of a portion of the structure of FIG. 1.

FIG. 3 is top plan view of the structure of FIG. 1.

FIG. 4 is a rear elevation view of the structure of FIG. 1.

FIG. 5 is a side elevation view of the side of the structure shown at the left in FIG. 1 and FIG. 3.

FIG. 6 is a side elevation view of the opposite side of the structure shown at the right in FIG. 1 and FIG. 3.

I claim:

The ornamental design for a window sash guide, substantially as shown.
